(57) CLAIM

The ornamental design for a swimming pool brush, as shown and described.

DESCRIPTION

FIG. 1 is a front perspective view of a swimming pool brush showing my new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof; and,

FIG. 8 is a right side elevation view thereof.

The dashed lines illustrate portions of the swimming pool brush that form no part of the claimed design.
